CLAIM

The ornamental design for a seatbelt adaptor, as shown and described.

DESCRIPTION

FIG. 1 is a top front left isometric view of a seatbelt adaptor in accordance with the present invention;

FIG. 2 is a bottom rear right isometric view of the seatbelt adaptor illustrated in FIG. 1;

FIG. 3 is a top view of the seatbelt adaptor illustrated in FIG. 1;

FIG. 4 is a left side view of the seatbelt adaptor illustrated in FIG. 1, the right side being a mirror image thereof;

FIG. 5 is a bottom view of the seatbelt adaptor illustrated in FIG. 1;

FIG. 6 is a front view of the seatbelt adaptor illustrated in FIG. 1;

FIG. 7 is a rear view of the seatbelt adaptor illustrated in FIG. 1;

FIG. 8 is a sectional view taken along line 8—8 in FIG. 3; and, FIG. 9 is a top front left isometric view of the a seatbelt adaptor illustrated in FIG. 1.

The phantom lines showing in FIG. 9 are for environmental purposes only and form no part of the claimed design.
